UNITED STATES PATENT OFFICE.

ANDREW T. PRATHER, OF RODEO, NEW MEXICO.

ATTACHING MEANS FOR GUN-SILENCERS.

Specification of Letters Patent.

Patented Feb. 8, 1916.

1,171,242.

Application filed November 14, 1914. Serial No. 872,150.

To all whom it may concern:

Be it known that I, ANDREW T. PRATHER, a citizen of the United States, and a resident of Rodeo, in the county of Grant and State of New Mexico, have invented a new and Improved Attaching Means for Gun-Silencers, of which the following is a full, clear, and exact description.

My invention has for its object to provide means for securing a gun silencer to the muzzle of a gun in a manner which will direct all the explosive gases through the silencer, thereby preventing any escape of the gases rearwardly between the fastening means and the barrel of the gun.

Additional objects of the invention will appear in the following specification, in which the preferred form of my invention is described.

20 In the drawings similar reference characters refer to similar parts in all of the views, in which—

Figure 1 is a view showing a gun silencer attached by my improved means to the muzzle of a gun. Fig. 2 is an enlarged sectional view of Fig. 1; Fig. 3 is a sectional plan view of Fig. 2; Fig. 4 is a transverse sectional view on the line 4—4 in Fig. 1; and Fig. 5 is a perspective view showing the 30 sleeve used with my fastening means.

The drawings show my invention used with a gun having a barrel 10 angular in cross section. With a gun having such a barrel, it is impossible, as now provided to prevent the explosive gases from passing rearwardly from the muzzle of the gun between the gun barrel and the means which are used for attaching the silencer to the gun barrel. With my invention, this difficulty is overcome, for the sleeve 11 which is secured around the muzzle 12 of the gun barrel 10, has a threaded opening 13 in which meshes the outer thread on a nipple 14, the nipple being turned home against the end of the muzzle 12. This makes a tight joint between the muzzle 12 of the gun and the sleeve 11, thereby preventing any of the explosive gases from passing rearwardly between the sleeve 11 and the muzzle 12. The nipple 14 projects beyond the sleeve 11 and meshes in a threaded opening 15 in the silencer 16 in the usual manner. In the drawings, I show a silencer of the Maxim type, but it will be understood that other types of silencers may be used with my invention.

As will best be seen by referring to Fig. 5 of the drawings, the sleeve 11 has a longitudinal slot 17 and a slot 18 at the opposite side, the slot 17 being provided to permit the arms 19 of the sleeve 11 to pass rearwardly of the gun sight or other projection 20 on the barrel 10. In the arms 19 there are grooves 21 in which are disposed the ends 22 of a transverse strap 23. The ends 65 of this transverse strap 23 are secured to the arms 21 by the set screws 24, which are disposed through the orifices 25 in the arms 19 and which mesh in threaded orifices 26 in the arms 19. When the strap 23 is disposed against the rear of the sight 20 and the nipple 14 is turned home against the end of the muzzle 12, the sleeve 11 will be held firmly in place relative to the gun barrel and when the outer end of the nipple 14 is 70 in mesh with the inner thread 15 on the silencer 16 and the silencer is turned home against the sleeve 11, it will be found that any escape of the explosive gases rearwardly of the muzzle of the gun between 75 the muzzle 12 and the sleeve 11, will be prevented.

Having thus described my invention, I claim as new and desire to secure by Letters Patent:—

1. In an article of the class described, a silencer with a threaded opening, a sleeve, means for securing the sleeve to the muzzle of a gun, the sleeve being provided with a threaded opening, and a nipple with an outer thread having one end meshing in the second threaded opening for abutting against the outer end of the muzzle of a gun, the other end of the nipple projecting 90 from the sleeve for meshing in the threaded opening in the silencer to permit the silencer to turn home against the sleeve to accommodate the adjustment of the sleeve relatively to the gun barrel.

2. In an article of the class described, a sleeve having a longitudinal slot, a band disposed across the slot, means for securing the ends of the band to the sleeve, there being an inner thread in the outer end of the sleeve, and a nipple with an outer 100 thread meshing with the thread in the sleeve for turning home against the muzzle of a gun disposed in the sleeve, the nipple projecting from the sleeve for the purpose specified.

3. In combination with a gun barrel having a projection and a silencer having a

threaded opening, a sleeve having a longitudinal slot in which the projection on the gun barrel is disposed, a band disposed across the slot in the rear of the projection, means for securing the ends of the band to the sleeve, there being an inner thread in the outer end of the sleeve; and a nipple with an outer thread meshing with the thread in the sleeve and abutting against the end of the gun barrel, the outer end of the nipple meshing in the threaded opening in the silencer to permit the silencer to turn home against the sleeve to accommodate the adjustment of the sleeve relatively to the gun barrel.

4. In combination with a gun barrel having a sight and a silencer having a threaded opening, a sleeve, means for securing the sleeve to the gun barrel relatively to the sight, there being an inner thread in the

outer end of the sleeve, and a nipple with an outer thread meshing with the thread in the sleeve and abutting against the end of the gun barrel, the outer end of the nipple meshing in the threaded opening in the silencer to permit the silencer to turn home against the sleeve to accommodate the adjustment of the sleeve relatively to the gun barrel.

In testimony whereof I have signed my name to this specification in the presence of two subscribing witnesses.

ANDREW T. PRATHER.
